RESILIENT FASTENER

Kenneth L. Johnson, Hampton Township, Allegheny County, Pa.

Application May 16, 1940, Serial No. 335,521

4 Claims. (Cl. 85—10)

This invention relates generally to fasteners and more particularly to fastenings designed to be driven into one member by repeated blows and having a resilient head and arm portion arranged to engage the member to be fastened.

This invention may be conveniently applied for securing railroad rails, plates, and track castings on supporting members such as crossties. Again these fasteners may be used in fabricated wood or metal structures as a substitute for nails, bolts and the like.

A resilient fastener is made of a single piece of metal and consists of a shank portion and an integral head portion having a laterally extending arm arranged to engage the member to be fastened when the shank is inserted into an anchored member. The resiliency of the fastener is produced by the flexure of the arm and the head portions of which there are a number of types. The art discloses resilient fasteners made from square bars and strip stock. In the former the original cross section is employed as the shank and the head and leg portions are forged so that they may be shaped and provide resiliency.

There are several types of resilient fasteners made from strip stock. Some of these are formed by doubling the strip back on itself to produce a laminated fastener and others are merely formed from a single continuous strip.

The form of these resilient fasteners with respect to their head and arm portions may be classified as two distinct types. In one type the impact receiving surface of the head is on the opposite side of the stock than the member engaging surface of the arm. In the other types the impact receiving surface of the head is on the same side of the stock as the member engaging surface of the arm. The former type includes those fasteners having their head and arm portions formed by merely bending over the stock. The same type may be made by bending the stock to one side of the shank and then back over the shank to the other side to form a head doubled back on its self. The other type includes those fasteners having their head portion formed either in a loop or in a twist. In each case the impact receiving surface is on the same side of the stock as the member engaging surface. The latter type consisting of the two distinct head forms is considered as a preferable structure.

Each of these types of resilient fasteners may be constructed from strip stock materially wider than it is thick. If this stock is approximately the same width as the dimension of a shank

5 of an ordinary cut spike it may be stiffened, to resist the bending caused by the off-center load application of the arm, by forming a rib longitudinally of the shank, which rib extends through the zone of maximum bending. If the width of 10 the stock is one and one-half times the dimension of an ordinary cut spike, or more, the shank may be stiffened by bending the side edges toward one another forming a stiffened shank substantially U-shape in cross section.

15 The laterally extending arm of these resilient fasteners overlies the member which is to be fastened. When used as spikes for resiliently holding railroad rails to crossties the engaging portion of the arm exerts a static load on the rail flange, which load is derived from the deflection of the arm created when driving the shank portion into the tie. The arm extends laterally and downwardly and the tip first engages the rail flange at a point spaced from the longitudinal axis of the shank. When the arm deflects as 20 the spike is driven into the tie this initial engagement at the tip of the arm is moved progressively away from the shank in line with the longitudinal axis of the arm and travels up the surface of the rail flange.

25 The purpose of these resilient fasteners is to permit the head and arm, which are subjected to partial deflection, to absorb the vertical wave motion and shock produced by the movement of trains along the track. As a train travels along the rails the propulsion effort sets up a force in the rails in the direction opposite to the travel of the train. The resistance to movement of the train sets up a force in the rails in the opposite direction or in the same direction as the travel of the train. These forces being opposed produce a resultant lifting force on the rails intermediate the length of the train, and since 30 the train is in motion these forces produce a traveling wave motion, causing the rails to raise from their support. This motion is absorbed by further flexure of the resilient portions of the spike and the hold down load of the spike increases with the flexure of the arm and head. A faulty road bed may accentuate the vertical movement of the rails when a train passes thereover. This is particularly noticeable at the rail joints.

35 It is believed that since the propulsion effort is applied over a shorter area than the resistive effort this progressive wave motion causes the track to creep in the direction of the movement of the train. Braking forces being applied for 40 retarding a train also causes the rails to creep

forward. It is general practice to employ rail anchors to resist this forward movement of the rails.

The principal object of this invention is the provision of a resilient rail fastener for not only securing the rail to the tie but also to retard the creepage of the rails.

Another object is the provision of a resilient rail fastener which is provided with a cutting edge for producing an engaging surface on the rail flange which is complementary to that on the fastener.

Other objects and advantages appear in the following description and claims.

In the accompanying drawing a practical embodiment illustrating the principles of the invention is shown wherein:

Fig. 1 is a perspective view of a resilient spike having a loop head structure for illustrating this invention.

Fig. 2 is a perspective view of a resilient spike, the head and arm of which are formed by merely bending over the upper portion of the stock.

Fig. 3 is a front elevation of a resilient spike having a twisted head.

Fig. 4 is a plan view showing the fasteners applied to a rail with the shank of each fastener disposed diagonally in the square spike hole in the tie plate, parts being broken away.

Fig. 5 is a sectional view of a resilient spike applied to a rail and taken on the line 5-5 of Fig. 4.

Fig. 6 is an inverted perspective of the tip of a resilient fastener arm showing the incisive portions of the engaging surface.

Fig. 7 is a view similar to that shown in Fig. 6, illustrating a modified form of the incisive portions of the engaging surface.

Fig. 8 is a view similar to Fig. 7 showing another modified form of the incisive portion of the engaging surface.

Fig. 9 is a longitudinal sectional view of another form of incisive portion.

Referring to the drawing the fastener 10 illustrated in Fig. 1 may be made from a strip approximately one and one-half inches wide and three sixteenths of an inch thick. A strip this wide could not pass through the square holes provided in a tie plate. Thus the shank portion 11 is formed by bending the longitudinal edges 12 toward one another, producing a partially enclosed cross sectional shape such as open tubular, U, V or C shape, depending upon the actual width of the strip and the conventional size of the hole through which the shank is to be driven. The edges may be in close proximity or even overlap. Thus the shank portion is stiffened to resist bending by shaping the stock into a longitudinal channel. The lower end of the shank is pointed for driving by pinching in the sides as indicated at 13.

This form of shank resists the bending moments at the point where it enters the member into which it is driven or through which it passes. The forces tending to bend the shank are created by the load application which is spaced from the neutral axis of the formed shank.

To form the loop head the edges 12 of the stock at the upper end of the shank gradually flare outwardly to the full stock width as shown at 14. The flat stock then curves smoothly from the upper end of the shank 11 into the looped head 15. The head is formed helical to permit the arm 16 to pass down on one side of the shank to the front of the spike. The under surface of the tip 17 engages the member to be fastened. The outer portion of this arm is straight and flat

and the under or engaging surface is the same as the impact receiving surface 18.

An incisive portion 20 is formed in the bottom edge of the arm tip 17 and the form of the profile thereof is extended back along the engaging surface of the arm as indicated at 21.

The fastener 22 shown in Fig. 2 is formed from a strip of approximately three quarters of an inch wide and three sixteenths of an inch thick. The straight shank 11 is pointed on its lower end at 13 for driving and is stiffened by the formation of the rib 23 longitudinally of the neutral axis of the shank. This rib should extend from the head 15 down along the shank through the zone of maximum bending which occurs adjacent the point of entry of the shank in the member into which it is driven or through which it passes. The bending forces, as mentioned above, are created by the off-center engagement of the load application. This rib preferably tapers from its full depth to the normal surface of the stock at each end thereof as indicated at 24.

The head 15 of the fastener shown in Fig. 2 is formed by merely bending over the upper portion of the stock to one side. It is preferably formed in a smooth continuous bend to avoid stress concentrations. The strip is then given a slight reverse curve at 25 to form the substantially straight arm 16. The under edge of the tip 17 of the arm is also provided with the incisive portion 20, the form of the profile of which is carried back in the under surface of the arm.

The spike 26 shown in Fig. 3 is made from the same stock of strip metal as that disclosed in Fig. 2 and has the same form of shank 11 with the stiffening rib 23. The head 15 of this fastener is formed by bending the upper portion of the strip over to one side and down in the same manner as that employed in forming the spike 22 of Fig. 2. The depending portion is then twisted toward the shank as indicated at 27 and bent laterally upward so that the arm 16 extends downwardly and outwardly with its neutral axis substantially parallel to the plane of the broad dimension of the shank. The impact engaging surface 18 is thus the same surface of the strip as the member engaging surface of the arm and the lower edge of the tip 17 is provided with the incisive portions 20.

When applied the axes of the arms of the resilient spikes are preferably disposed diagonally to the neutral axes of the rails. As shown in Fig. 4 the spike members 26 are driven through the standard square hole 28 in the tie plate 29 with the broad dimension disposed diagonally with the hole. The arms of the spikes are disposed at an angle substantially forty-five degrees to the axis of the rail 30. Left and right hand spikes are provided so that the arms of the spikes on opposite sides of the rail extend in the same general direction. This should be adopted for a track over which the trains pass in one direction only. If the traffic passes in both directions right hand spikes should be used on both sides of the rail and their arms would be extending in opposite directions. In Fig. 4 the traffic travels from right to left of the figure.

When the spikes are driven into position the incisive portions 30 gouge into the upper surfaces of the rail flanges 31, producing an initial cut therein which is complementary to their cutting profile. Repeated vertical movement of the rails due to traffic running thereover extends this cut in the surface of the flange beyond the tip 32 of the arm as indicated at 33. Repeated wave

motion in the track wears deep grooves in the flange surfaces. The angular disposition of the spikes together with the interlocking engagement between the resilient arms and the rail prevents it from creeping.

The standard cut spikes are ordinarily raised by this vertical movement of the rails and the creeping forces are resisted only by the rail anchors. With the resilient spike the static load is always subjected to the rails to hold them down. This load decreases the magnitude of the wave motion and when that point along the track under the train is at the peak of its movement the resilient fastener is applying its maximum force to hold it down. This action together with the interlocking between the arm and the rail, which is always effective regardless of the wave motion, prevents creepage of the rail.

In Fig. 5 the normal position of the spike is shown in full lines. The upper dotted lines show the spike as the incisor edge of the tip of the arm 16 engages the flange and the other dotted lines indicate the rail at the peak of the wave motion causing increased deflection of the arms. The vertical movement of the rail thus causes the arm to oscillate between the full and dotted line positions indicated.

Figs. 6, 7 and 8 show different characters of incisive portions 20 on the underside of the free end of the arms 16. The form shown in Fig. 6 may be milled or ground, whereas the forms shown in Figs. 7 and 8 may be forged or pressed during the forming operation of the spike.

A plurality of incisor cutting profiles 33 may be formed on the individual ridges as indicated in Fig. 9. If the spacing between aligned incisor profiles 33 is equal to or less than the normal longitudinal movement of the arm 16 relative to the rail then one profile 33 may take up the cutting action of the other and thereby increase the gripping action between the rail and the arm. The individual incisor teeth 33 may be formed by backing off the ridge of the teeth and thereby producing an abrupt cutting profile.

It has been generally accepted in the art that a resilient railroad rail fastener be designed to apply a load of a thousand pounds. The interfacial friction created by this load between the fastener and the rail flange may retard creepage of the rail to some degree. The wave motion produced in the rails by traffic is believed to be an irresistible force which will either flex the resilient fasteners or lift the ties from the road bed, or both.

Generally a resilient spike designed to apply a thousand pound load will flex and absorb a portion of the wave motion relative to the tie and the balance of this motion lifts the tie from the road bed. Vertical movement of the ties produces an undesirable condition which is detrimental to the road bed. In warm climates the oscillating action of the ties disturbs the road bed by pumping moisture to the surface of the road bed. In cold climates the ties will freeze in the road bed and will resist movement, thus requiring the resilient fastener to assume the full magnitude of the wave motion. If the resilient fastener is driven into the tie to a depth at which it applies a load of a thousand pounds to the rail flange and it is required to flex and absorb the full wave motion of the rails it will be worked beyond its elastic limit, thereby destroying the resilient characteristics and causing failure.

However it is desirable to require the resilient

spikes to assume the full wave motion to avoid disturbance of the ties. To accomplish this end the resilient load characteristics of the spikes must be decreased so that the initial hold down pressure is less than one thousand pounds. This may be accomplished in two ways; first, by reducing the load characteristics by designing a lighter spike, and secondly, by driving an ordinary spike designed to produce a thousand pound load under full deflection, to a lesser depth in the tie. Having been applied with the arm under partial deflection the initial load of the spike will be materially less than one thousand pounds. Under these conditions the full magnitude of the wave motion will be assumed by the spikes alone; the ties will remain in the road bed undisturbed; and the flexure of the spike will be completely within the elastic limit of the material.

The initial load pressure of a resilient spike driven until the arm is partially deflected is sufficient to maintain the interlocking engagement of the contacting surface comprising this invention. The resistance against creepage that may have been obtained with the interfacial frictional engagement of an applied load of one thousand pounds is more than compensated for by the interlocking engagement applied under loads of a fractional part thereof. Again this interlocking engagement prevents rail creepage with the additional advantage of not disturbing the ties in the road bed.

The initial pressure of the resilient spike is sufficient to hold the incisors in their complementary formed surfaces on the top of the rail flanges, which is a positive check against rail creepage, whereas interfacial frictional engagement may merely retard creepage.

The full magnitude of the wave motion is absorbed by the resilient spikes which have a reduced initial load application. The repeated flexure of the resilient arms of these spikes due to the wave motion in the rails, causes the cutting profiles of the incisor portions to cut to the full depth of the incisors forming the interlocking surfaces. Since these surfaces are disposed at an angle to the creepage of the rails they resist longitudinal advancement of the rail in the direction of the traffic.

I claim:

1. A resilient railway spike comprising a relatively stiff shank for driving into a tie, an integral resilient arm arranged to flex intermediate of its free extremity and the shank and having its outer portion normally depending at an acute angle with the shank, and incisive portions on the free end of the resilient arm arranged to engage and cut extended complementary grooves in the top surface of a rail flange.

2. A resilient railway spike comprising a relatively stiff shank for driving into a tie, an integral resilient arm arranged to flex intermediate of its free extremity and the shank and having its outer portion normally depending at an acute angle with the shank, and incisive portions on the free end of the resilient arm arranged to engage and cut extended complementary grooves in the top surface of a rail flange, said incisive portions being substantially parallel to the longitudinal axis of the arm.

3. A resilient railway spike comprising a relatively stiff shank for driving into a tie, an integral resilient arm arranged to flex intermediate of its free extremity and the shank and having its outer portion normally depending at an acute

angle with the shank, and a series of aligned incisive portions on the under face of the free end of the resilient arm arranged to engage and cut extended grooves in the top surface of the rail flange by the driving action of the spike and by the lifting movement of the rail when traffic moves thereover.

4. A resilient railway spike comprising a shank arranged to be secured to a railway tie, a flexible arm integral with the shank, said arm curving

10

downwardly at an acute angle to the shank and contacting the work below the point of maximum flexure, and incisive means having a cutting profile on the contacting surface of the arm arranged to cut a complementary form in the surface of the work when the spike is applied thereto, said incisive means remaining in interengagement with the cut form to prevent lateral movement between the spike and the work.

KENNETH L. JOHNSON.
